UNITED STATES PATENT OFFICE.

ALBERT F. NORRIS, OF STOUGHTON, AND CLIFTON H. NORRIS, OF BOSTON,
MASSACHUSETTS.

DESIGN FOR A PEDAL.

51,238.

Specification for Design.

Patented Sept. 4, 1917.

Application filed May 1, 1917. Serial No. 165,795. Term of patent 7 years.

To all whom it may concern:

Be it known that we, ALBERT F. NORRIS and CLIFTON H. NORRIS, citizens of the United States, residing at Stoughton, in the county of Norfolk and State of Massachusetts, and Boston, in the county of Suffolk and State of Massachusetts, respectively, have invented a new, original, and ornamental Design for Pedals, as shown in the accompanying drawing and described in the following specification.

In the drawings:

Figure 1 is a perspective view of the pedal illustrating my new design.

Fig. 2 is a plan view thereof.

Fig. 3 is a front end view of Fig. 2, and Fig. 4 is a side elevation of Fig. 2.

In the novel design of the pedal contemplated in the present invention there is provided a rearwardly extending, relatively straight shank 2 which is provided with suitable apertures 3. At the front end of the stem or shank 2 is provided an upwardly extending projection 4 and on the lower side of the stem is a perpendicular downwardly extending shoulder 5 from which projects forwardly in a plane somewhat below the plane of the stem or shank 2 the front end or body portion 6, the lower surface of which is substantially flat, the

outer end of which is circular as shown in plan, and has slightly upwardly tapering sides overlapped at the top by a circular button 8 which occupies a position at the front end of the body portion 6, the latter being provided with upwardly beveled and convergent sides 7 which meet in an apex or ridge line which is continued at the rear in a curved upwardly extending line terminating in front of the upright projection 4.

The front circular end of the body is of somewhat larger diameter than the width of the pedal stem or shank 2, the sides of the body 6 converging rearwardly from the front and enlarged end toward the laterally projecting portions 4 and 5 at the stem.

The ornamentation in this pedal resides especially in the graceful outline of that part which is exposed to view when the pedal is in place on a piano, and which has at its outer end the conic frustum capped with a disk-like crown of greater diameter than the width of the shank 6, the latter being chamfered to a central medial ridge.

We claim:

The ornamental design for a pedal as shown and described.

ALBERT F. NORRIS.
CLIFTON H. NORRIS.
